Primary Examiner—Bernard Ansher*Assistant Examiner*—Sandra Morris*Attorney, Agent, or Firm*—Richard C. Litman**[57] CLAIM**

The ornamental design for a mower cutting head, as shown and described.

DESCRIPTION

FIG. 1 is a bottom and side environmental perspective view of a mower cutting head showing my new design, the portion of the figure shown in broken lines representing a mower and forming no part of the claimed design;

FIG. 2 is a top plan view thereof;

FIG. 3 is a bottom plan view thereof;

FIG. 4 is a side elevational view thereof, the opposite side being a mirror image; and,

FIG. 5 is a front elevational view thereof, the rear elevational view being a mirror image.
